CARRYING CASE FOR PICTURE PROJECTING APPARATUS

Frank Freimann, Fort Wayne, Ind., assignor to
Electro-Acoustic Products Company, Fort
Wayne, Ind., a corporation of Illinois

Application July 16, 1935, Serial No. 31,632

6 Claims. (Cl. 88—24)

The present invention relates to sound reproducing and picture projecting apparatus and more particularly to a novel arrangement of parts and a carrying case therefor, by means of which the apparatus may be easily transported from one place to another and is a continuation in part of my co-pending application, Serial Number 740,448, filed August 18, 1934, and entitled Carrying case.

An object of the present invention is to provide a carrying case for a picture projecting apparatus which is useful in operation and compact and novel in construction.

Another object of the invention is to provide a carrying case for sound reproducing and picture projecting apparatus having a lantern supporting panel that may be adjusted to different positions to control the angle of picture projecting and which will conceal the lantern in an inoperative and protected position when closed.

Another object of the invention is to provide, in the combination of a carrying case and a picture projecting apparatus of the character described, an operating means for the lantern which will permit an operation thereof in a novel and convenient manner.

Another object of the invention is to provide, in the combination of a carrying case and a picture projecting apparatus, a new and novel control means for the picture projecting apparatus, by means of which said apparatus may be controlled from a remote point.

Another object of the invention is to provide, in a carrying case of the character described, a supporting element for a picture projecting apparatus which will permit an operation thereof at a point externally of the carrying case where a free circulation of cool air may exist thereabout.

Further objects and advantages of the invention will be in part evident to those skilled in the art and in part specifically pointed out as the description thereof proceeds.

For a better understanding of the invention reference should be had to the accompanying drawings wherein there is shown by way of illustration and not of limitation, a preferred embodiment thereof.

In the drawings:

Figure 1 is a perspective view showing apparatus in a carrying case of the type contemplated by this invention with the case fully opened and with the apparatus in an operative position,

Figure 2 is a perspective view of a cover for the carrying case illustrated in Figure 1.

Figure 3 is a back view in perspective of the apparatus shown in Figure 1, with the cover in its closed position upon the case, 5

Figure 4 is a fragmentary perspective view showing in detail an improved form of operating mechanism for the picture projecting apparatus.

Figure 5 is a perspective view of a framing 10 and hand operating knob removed from the assembly illustrated in Figure 4,

Figure 6 is an enlarged fragmentary sectional view showing a modified form of operating mechanism for the picture projecting apparatus, 15

Figures 7 and 8 are fragmentary sectional views showing details of the picture film advancing mechanism,

Figure 9 is a fragmentary view with parts broken away showing a further modified form of 20 operating mechanism for advancing the picture film of the projecting apparatus,

Figures 10 and 11 are enlarged fragmentary views showing details of the picture film advancing mechanism, and 25

Figure 12 is a fragmentary view partially in section and with parts broken away to show the means of supporting and elevating the picture projecting lantern.

As illustrated in the drawings, the present 30 invention is embodied in a new and novel carrying case for transporting a combined sound reproducing and picture projecting apparatus which may be quickly set up for operation in a simple and convenient manner. A feature of 35 the carrying case is that, when closed, it will hold the several elements of the unit in a protected manner so that they will not become damaged or rendered inoperative when transported from one place to another. 40

The carrying case illustrated in Figures 1, 3 and 6 of the drawings comprises a rectangular housing 10 having a horizontally hinged panel 11 at one end thereof and a comparatively deep cover 12 which is adapted to be secured 45 upon and form a closure for the top of the housing 10. Disposed across the top of the housing 10 there is a panel 13 which supports a tone arm carrying pedestal 14 and a cooperating sound record support. The sound record support comprises an upwardly projecting vertically disposed shaft 15 having a sound record supporting platen 16 thereupon. A tone arm 17 is pivotally mounted upon the pedestal 14 in 50 cooperating relation with the sound record sup- 55

porting platen 16. At the end of the tone arm 17 there is an electromagnetic pick-up device 18 having a needle which is adapted to engage and reproduce sound from a disc type of record, 5 designated by the numeral 19.

Electrically connected with the electromagnetic pick-up device 18 is a thermionic tube amplifier 20 for amplifying the sound currents generated thereby and connected with the output of the amplifier 20 is an electrodynamic loud speaker 21. The loud speaker 21 is shown mounted over a sound opening which is preferably formed in one of the sides of the housing 10 so that the sound emanating therefrom will be directed toward the 10 audience when the apparatus is set up at one side of a room, as would be the case where the apparatus is to be used for the instruction and/or amusement of a small audience. In a preferred arrangement of this aspect of the present invention 15 the loud speaker 21 is demountably supported upon the side of the carrying case so that it may be removed and mounted upon a suitable baffle, which can be placed at any convenient point remote from the apparatus, as for instance, 20 adjacent the picture screen in front of the audience. Such a mounting forms the subject matter of a co-pending application for patent, Serial Number 22,887, filed May 22, 1935, by J. L. Freisner and myself, as joint inventors.

30 As illustrated in Figure 1 of the drawings, the platen supporting shaft 15 projects up through the panel 13 and is driven by an electric motor mechanism 22 secured to the underside of the panel 13. A controlling lever 23 by means of which the speed of the shaft 15 may be determined, projects upwardly through the panel 13 and is disposed at a point adjacent the periphery of the record supporting platen 16 where it can be conveniently operated. Adjacent the lever 23 35 there is also an operating knob 24 for controlling the tonal output of the amplifier 20.

The amplifier 20, the electrodynamic loud speaker 21 and the motor mechanism 22 are adapted to be operated from an ordinary house 40 current outlet and therefore the apparatus is provided with a suitable lead (not shown) which carries a service outlet plug. Associated with this lead and mounted upon the panel 13, there is a toggle switch 25, by means of which the 45 current supply may be shut off and turned on without pulling the plug from its supply outlet.

In addition to the above described sound reproducing apparatus, the housing 10 is adapted to also support a picture projecting apparatus. 50 As shown in the drawings, this apparatus comprises a picture projecting lantern 26 having a lens system 27, a picture film support 28 and a film advancing mechanism 29.

The picture projecting apparatus is mounted 55 upon the inside of the panel 11 so that when it is closed this apparatus will be concealed within the housing 10. To provide for a variation in the angle of projection and to determine the elevation at which the picture is to be reproduced, 60 upon a wall or screen, the panel 11 is provided with one or two adjustable brackets 30 which may be secured by thumb screws 31 to hold the panel 11 at any desired angle with respect to the housing 10. The picture record contemplated for 65 use with the lantern illustrated may comprise a series of pictures formed upon standard motion picture film. To facilitate the use of such a picture film the advancing mechanism 29 is made so that it will automatically advance the film 70 one frame at a time. The construction and oper-

ation of this aspect of my invention is to be described in more detail hereinafter.

A film record of the above character can be made up with any number of pictures and used without supporting reels, the film being rolled up 5 in a free coil which can be inserted in the film support 28. In operation the film passes before the lens system 27 and after it is used it can be rolled up by hand and placed in a suitable container. Four of these containers, designated by 10 the numeral 32, are shown as fixed to the inside of the cover 12.

In order that the film may progress freely through the advancing mechanism 29, it is passed through a slot 33 formed in the hinged 15 panel 11. The projection of the film through the slot 33 permits it to hang free of the apparatus where it cannot become entangled therewith or curl up in front of the lens system 27 and interfere with the projection of subsequent 20 pictures.

Should the sound record 19 relate to a lecture or a sales talk, which is to be illustrated by pictures arranged in a proper sequence upon the picture film, it is intended that the record will be 25 provided with a sound signal which will indicate when the picture film is to be advanced. In practice it has been found that a musical note interspersed with the spoken program may be resorted to for this purpose.

30 Instead of the still picture projecting apparatus, described above, the panel 11 may be provided with a moving picture projecting machine. In this latter event it will be possible to reproduce synchronized action pictures and sound by starting 35 the picture film and sound record at the proper synchronizing points.

When the hinged panel 11 is in its closed position, the weight of the picture projecting apparatus secured thereupon will operate, because of its 40 weight, to hold the panel 11 in its closed position. However, for safety the panel 11 has a spring 45 pressed bolt 34 which will engage the top of the opening when the panel 11 is closed. With this latter described arrangement, it will be seen that the picture projecting apparatus can be placed in an operative position by merely opening the hinged panel 11 and adjusting it for the proper angle of projection by tightening the thumb screws 31 upon the brackets 30.

50 As shown, the sound record supporting platen 16 is of a larger diameter than the width of the housing 10. For compactness, the sound record supporting platen 16 is made so that it can be removed from the shaft 15 and placed, together with one or more records, in a vertical compartment 35 provided at one side of the housing 10. After the sound record supporting platen 16 has been placed in the compartment 35 the cover 12 can be closed upon the housing 10, as illustrated 55 in Figure 2 of the drawings, where it can be secured in its closed position by two oppositely placed spring clasps 36. The cover 12 also has a suitable grip or handle 37 on the top thereof, by means of which the carrying case may be 60 easily handled.

65 Before proceeding with a description of the picture film advancing mechanism, attention is directed to the lamp enclosing housing of the lantern 26, at the bottom of which there is provided a flue 38 through which air may enter and circulate up through the housing. This flue 38 70 may stop short of the hinged panel 11 or it may be extended therethrough, as desired. In a modification of this feature, the hinged panel 11 may, 75

as shown in Figure 3 of the drawings, be provided with a screened opening 39, through which a circulation of air may pass upwardly through and about the lamp housing of the lantern 26. 5 As shown in Figure 3 of the drawings, the film advancing mechanism 29 is adapted to be operated by a pull cord 40, which terminates upon one arm of a bell crank 41. The free end of the bell crank 41 is provided with a thumb rest 42 upon which pressure may be applied to operate the advancing mechanism 29 through the pull cord 40. With this arrangement it will be seen that the operator may, when standing at the rear of the projection apparatus and adjacent the carrying case, advance the film by simply pressing upon the thumb rest 42. The bell crank 41 is so mounted that it may be rotated into the carrying case 10 and concealed by a hinged door which, when open, provides access to this end 15 of the carrying case. In the event that through necessity, or convenience, the operator should desire to seat himself at the rear of the room remote from the apparatus, he can by simply attaching an extension cord 43 to the bell crank 20 41, as shown, operate the film advancing mechanism from any distance, depending upon the length of the extension cord 43 so provided. Cooperating with the bell crank 41 there is also provided a suitable clip 44 which will serve to 25 retain the bell crank in a retracted position within the carrying case 10.

As illustrated in Figure 4 of the drawings, the film advancing mechanism 29 comprises a ratchet wheel 45 which is connected to a pair of spaced film advancing sprockets by means of a shaft 46. Mounted freely upon a shaft 46 and biased outwardly by a spring 47 is a lever 48 and pivotally mounted upon the lever 48 there is a ratchet engaging pawl 49 that is biased by means of a spring 50 into engagement with the ratchet wheel 45. The lever 48, when in its outermost position, engages a stop 51 carried by a suitable bracket 52. The length and range of movement of the lever 48 is such that upon a full movement thereof, the picture film will be moved a distance corresponding to one picture frame. In order to permit operation of the film advancing mechanism, as for instance in framing the first picture, the shaft 46 is provided with an operating knob 53, such as is illustrated in Figure 5 of the drawings. In framing a picture in this manner, the pawl 49 may, if necessary, be disengaged from the ratchet wheel 45 to permit a backward movement of the picture film.

In Figures 6, 7 and 8 of the drawings, there is shown a modified form of the film advancing mechanism. As here illustrated, the operating lever 48 is connected through a pin 54 and a slotted link 55 with a slidable rod 56 that is mounted upon spaced bearings 57 adjacent the lantern housing. The slidable rod 56 is biased to an outward position by the spring which returns the lever 48, and at its rear end it is connected through a short length of pull chain 58 with a second slidably mounted rod 59 that extends through to the rear door of the carrying case 10. The rod 59 is here illustrated as slidably supported upon spaced supports 60.

It will be evident that with the above and the previously described arrangement, the film advancing mechanism may be successfully and effectively operated when the lantern is positioned at any of its normal picture projecting angular positions.

In Figures 7 and 8 of the drawings, there is illus-

trated the details of a preferred form of film advancing mechanism. As shown, this mechanism comprises a pair of spaced film engaging sprockets 61 mounted upon a hub 62. The hub 62 is splined to an axially movable shaft 63 so that the sprockets 61 may be rotated any desired degree by means of a knob 64 carried at the end thereof. The sprockets 61 and the shaft 63 are mounted in a suitable metal housing 65 and the teeth of the sprockets 61 project through and engage the sprocket apertures of a film as it passes through the film guiding frame. Mounted freely upon the shaft 63 and within the housing 65 there is a four point ratchet 66 which is held in frictional driving engagement with the shaft 63 by means of a spring 67. The spring 67 is secured to the shaft 63 and is so constructed that the ratchet 66 will be released from the shaft 63 when the shaft is in its outermost position. This will permit a framing of the picture without displacing the ratchet 66 from its operative relation to the operating pawl 69. Journaled upon the side of the housing 65 and adjacent the ratchet 66, is a rotatable plate 68 to which the operating lever 48 is connected. The plate 68 carries a pawl 69 that is adapted to cooperate with the four teeth of the ratchet 66 and move the same one-quarter of a revolution each time the operating lever 48 is actuated in the manner above described. In this arrangement a spiral spring 70 serves to return the operating lever 48 and the pawl carrying plate 68 back to their initial starting positions. Upon the ratchet 66, and adjacent the teeth thereof, is a squared portion 71 upon which a pressure spring 72 is adapted to rest. The function of the spring 72 is to insure a full quarter revolution of the sprocket wheels 61 and in this connection the spring 72 operates to carry the ratchet wheel 66 into its final position and retain it there while the lever 48 and the pawl 69 are retracted into position for a subsequent advance of the picture film.

In Figure 9 of the drawings there is shown a further modified form of film advancing mechanism wherein there is provided a permanently connected linkage through which movement is imparted to the film advancing sprockets from a position at the rear of the carrying case. As here shown the film sprocket operating lever 48 carries a floating link 73 which connects with the lower end of a pivotally mounted lever 74. The lever 74 is pivoted upon a pin 75 and intermediate its ends there is connected a second floating lever 76 that extends rearwardly through the carrying case 10. The rear end of the floating link 76 is pivotally connected to a lever 78 which is pivoted at its lower end upon a pin 79. Also mounted upon the pin 79 there is a rotatable disc 80 which carries a thumb rest 81. The disc 80 also carries a pin 82 that is positioned to engage the lever 78 and move it rearwardly when a downward pressure is exerted upon the thumb rest 81. The pin 82 merely engages the side of the lever 78 and as a result it is possible to rotate the disc 80 clockwise a distance sufficient to permit the thumb rest 81 to be enclosed within the carrying case when the rear door, designated by the numeral 83, is closed. In this arrangement the lantern supporting panel 11 is mounted upon supporting pivots 84 so that it may be rotated in a counter-clockwise direction to close the front end of the carrying case and support the lantern 26 in a concealed position. The supporting panel 11 here shown is constructed of metal and it has oppositely disposed upwardly extending brackets 75

85 which engage the pins 75 at each side of the carrying case opening and support the panel 11 in a substantially horizontal position.

In apparatus of this character, it is sometimes desirable to remove the lantern 26 and therefore the floating link 73 is provided with a keyhole slot 86 which permits a detachment thereof from the film operating lever 48. The lantern in this instance is shown as secured upon the supporting panel 11 by means of removable thumbscrews 87 located on opposite sides of the lantern. In this embodiment of the invention, the film support 28 is shown as provided with a film retaining lever 88, which may be lifted to permit insertion of a roll of film and which, when down as shown, will serve to retain the roll of film in the support. As a further improvement the amplifier volume control knob 24 and the phonograph controlling toggle switch 25 are shown as mounted upon a panel 89 located at the rear of the carrying case adjacent the film advancing thumb rest 81.

With the above arrangement of linkage it will be seen that the lantern 26 may be rotated back into its concealed position without disturbing the connections of the linkage mechanism as the lever 74 will float about its pivot 75 and the lever 78 will rotate freely about its pivot 79 and permit the mechanism to assume the position illustrated by dot and dash lines.

In Figures 10 and 11 of the drawings there is shown in detail a further modified form of film advancing mechanism with which there is associated a film holding means that serves to surface the film upon the framing aperture of the lens system of the projection lantern. As here shown the film engaging sprockets designated by the numeral 90 are mounted horizontally in the housing 65 and associated therewith is a ratchet 91 with which a pawl 92 is adapted to cooperate. The pawl 92 is carried by a plate 93 which is connected with the operating lever 48. The pawl 92 is biased into engagement with the ratchet 91 by means of a spring 94, and when the operating lever 48 is operated upon by the floating link 73, the ratchet 91 will be turned one-quarter of a revolution and thus advance the film one full picture. In order to insure a full and complete one-quarter turn of the ratchet 91, there is associated therewith a pressure bar 95 which is biased about a pivot shaft 96 by a tension spring 97. The teeth upon the ratchet 91 are so disposed and shaped that they will provide a series of right angle surfaces upon the face of the ratchet 91 against which the pressure bar 95 may rest.

against which the pressure bar 35 may rest. At its inner end the ratchet 91 is provided with a cam forming extension 98 against which one arm of a yoke 99 is yieldingly held by means of a spring 100. The arms of the yoke 99 are pivoted at their lower ends upon the pivot shaft 96 and at its upper end the yoke 99 carries upwardly extending arms 101 which carry a pressure exerting glass 102 that is adapted to engage the film as it passes through the framing housing and there hold the film firmly and smoothly in the framing aperture. The glass 102 is mounted in a suitable frame 103 which carries rearwardly projecting pins 104 that engage the arms 101. To provide for a yielding pressure by the glass 102 there is interposed between the arms 101 and the frame 103 a pair of compression springs 105. A spring 106 is here shown for returning the plate 93 with the pawl 92 to their initial position.

With this arrangement it will be readily seen
75 that as the pawl 92 operates to turn the ratchet

91 and advance the film, the cam surface 98 will also rotate and by virtue of its contour cause the yoke 99 to rotate outwardly about the pivot shaft 36 and lift the pressure producing glass 102 out of engagement with the film and permit its free movement through the framing mechanism. It will also be seen that when the operating lever is rotated through a full film advancing movement the pressure bar 95 will move outwardly and extend its tension spring 97 until a maximum outward position is assumed, after which the pressure bar 95 will move inwardly under the influence of the spring 97 and assist in turning the ratchet 91 into a subsequent film framing position. 15 10

Upon referring to Figure 12 of the drawings it will be seen that the lantern supporting panel 11 is adapted to come to rest when the brackets 85 at each side thereof come into engagement with the pins 75. When the projection lantern is secured upon the supporting panel 11, as illustrated in Figure 9 of the drawings, the picture screen will need to be adjusted in elevation to suit the projection angle of the lantern. To remedy this the lantern is shown, in Figure 12 of the drawings, as provided with rearwardly projecting arms 107 which are pivotally secured upon the pivot points 84 about which the supporting panel 11 moves. Beneath the lantern and in an outwardly disposed position there is a suitable lantern elevating device by means of which the lantern may be elevated through a limited vertical arc independently of the supporting panel 11. This elevating device, in its preferred form, comprises a cup-like member 108 which is rotatably mounted upon the supporting panel 11. The cup-like member 108 has an operating lever 109 and in oppositely disposed positions it is provided with spirally disposed slots 110 into which project oppositely disposed pins 111 located upon the bottom of the lantern 26. The inclination and pitch of the spirally disposed slots 110 are such that when the lever 109 is pulled outwardly from the lantern the pins 111 will ride upwardly in the slots 110 and thus elevate the front of the projection lantern 26. In order to hold the lantern 26 against the supporting panel 11 when the carrying case is closed, the spiral slots 110 are provided with a short flat portion 112 at the lower ends thereof.

From the above description it will be seen that I have provided a convenient and novel form of combined carrying case and a lantern supporting means in which the angular projection of the lantern may be adjusted to any suitable angle without at the same time disturbing the level of the sound record platen which, as is well known, should operate on a substantially level plane in order to secure proper cooperation with the delicately balanced electromagnetic pick-up device such as is commonly used with apparatus of this character. Another novel feature of the present invention is that the picture advancing mechanism can be operated while the lantern is in any of its normal angular positions without requiring any adjustments between the film advancing means and the operating means at the rear of the carrying case, and that the hinged panel 11 which supports the picture projecting lantern can be freely opened and closed without requiring any detachment of the operating mechanism. Another important advantage in the arrangement of my present invention is the provision of a combined carrying case and lantern support wherein the lantern may be conveniently moved and ex- 75

peditiously adjusted in an operative position externally of the carrying case where a natural circulation of cooling air will exist when the lantern is in operation.

5 While I have, for the sake of clearness and in order to disclose my invention so that the same can be readily understood, described and illustrated specific devices and arrangements, I desire to have it understood that this invention is 10 not limited to the specific means disclosed, but may be embodied in other ways that will suggest themselves to persons skilled in the art. It is believed that this invention is new and it is desired to claim it so that all such changes as come with 15 in the scope of the appended claims are to be considered as part of this invention.

Having thus described my invention, what I claim and desire to secure by Letters Patent is—

1. In apparatus of the character described, the 20 combination of a carrying case having an opening in one end, an extendible support disposed in the open end of said carrying case upon which a picture projecting lantern may be secured, said extendible support being such that when extended it will support the picture projecting lantern in an operable position externally of said carrying case, and when not extended it will form a closure for the opening in the end wall of said carrying case and conceal the picture projecting 25 lantern therein, a picture projecting lantern mounted upon and movable with said extendible support, a picture film advancing mechanism carried by and movable with said lantern, a crank arm associated with said film advancing mechanism by means mounted in a fixed position upon the carrying case remote from said film advancing mechanism, a link extending from said last means toward the crank upon said film advancing mechanism, a second link extending from the 30 crank upon said film advancing mechanism and terminating adjacent the end of said first link, and a pivotally mounted lever forming an articulated connection between said links having an overcentering action which will render the manually operable means upon said carrying case effective to actuate the crank arm of said film advancing mechanism when the lantern and its support is extended from said carrying case and ineffective to operate said crank arm when said 35 lantern is enclosed within said carrying case.

2. In apparatus of the character described, the combination of a carrying case for a picture projecting lantern, a hinged support at one end of said carrying case upon which a picture projecting lantern may be mounted and moved in its 40 entirety from an inoperative position within the carrying case to an operative position externally of the carrying case and vice versa, a picture projecting lantern mounted upon and movable in its entirety with said hinged support, a picture film advancing mechanism upon said lantern also movable with said support, a link connected at one end to said picture advancing mechanism and extending to a point adjacent the hinge of 45 said support, a second link extending through said casing from a fixed point at the rear thereof to a point adjacent said hinge, and a lever secured to said carrying case and connected to the adjacent ends of said links forming a support 50 and an articulated connection between said links, whereby the picture projecting lantern may be moved with said extendible support between its inoperative and operative positions and vice versa without a disconnection of said links.

75 3. In a power operated sound and picture re-

producing apparatus, the combination of a carrying case constructed and arranged to enclose the apparatus while not in use and to support the apparatus in an operative position while the case is open, sound reproducing apparatus carried by said case, a movable lantern supporting means mounted upon and extendible from one wall of said case in such manner as to support a picture projecting lantern externally of the carrying case, a picture projecting lantern mounted upon said supporting 10 means, a film advancing mechanism upon said lantern, actuating means for said film advancing mechanism mounted at a fixed location upon said carrying case remote from said lantern supporting means, and operating means connecting said film advancing means and said actuating means and means limiting movement of the actuating means in one direction, said operating means containing a portion which renders the same inoperative while the lantern is in its inoperative position within the carrying case.

4. An electrically operated sound and picture reproducing apparatus in combination with a portable hand carrying case having a main section and a cover section to house both the sound 25 and picture reproducing apparatus when not in use and to support said apparatus in an operative exposed position when the case is open, a sound reproducing apparatus mounted in the main section of said case and comprising electric 30 sound record reproducing apparatus exposed for operation when the cover is removed, an electric amplifying apparatus located in the lower part of the main section with its loud speaker opening through a side wall of said case, a vertical end 35 wall of said case having an opening therein, a vertically swinging panel pivoted at its lower end in said opening, and a picture projection apparatus mounted on said panel and completely housed within said case when not in use, said panel when 40 swung about its pivot moving said projection apparatus outwardly and away from said case into operative position.

5. An electrically operated sound and picture reproducing apparatus in combination with a 45 hand carrying portable case having a main section and a cover section to house both the sound and picture reproducing apparatus when not in use and to support said apparatus in an operative exposed position when the case is open, sound reproducing apparatus mounted in the main section of said case and comprising electric sound record reproducing apparatus exposed for operation when the cover is removed, an electric amplifying apparatus located in the lower part of the main 50 section with its loud speaker opening through a side wall of said case, a vertical wall of said case having an opening therein, a movable member mounted in and co-extensive with said opening, and picture projecting apparatus mounted on 55 said member and completely housed within the case when the member is in its coextensive position, said member being movable outwardly of said case to a horizontal position to bring the picture projecting apparatus into an operative position entirely without the case to protect the sound apparatus from the heat of the projector and to permit free circulation of cooling air to the projecting apparatus.

6. An electrically operated sound and picture 70 reproducing apparatus in combination with a hand carrying portable case having a main section and a cover section to house both the sound and picture reproducing apparatus when not in use and to support said apparatus in an operative 75

exposed position when the case is open, sound reproducing apparatus mounted in the main section of said case and comprising electric sound record reproducing apparatus exposed for operation when the cover is removed, an electric amplifying apparatus located in the lower part of the main section with its loud speaker opening through a side wall of said case, a vertical wall of said case having an opening therein, projector supporting means attached to said case and ex-

tensible through said opening, and picture projection apparatus mounted on said means and completely housed within said case in inoperative position when said means is retracted and supported by said means outwardly and away from said case when said means is in extended position to protect the sound apparatus from the heat of the projector and to permit free circulation of cooling air to the projecting apparatus. 5

FRANK FREIMANN. 10
